SCHOOL PLAQUE OR THE LIKE

Clyde Ray Minix, P.O. Box 366,
Edwardsburg, Mich. 49112

Filed July 1, 1965, Ser. No. 85,985

Term of patent 3½ years

(Cl. D29—23)

FIG. 1

The back of the plaque is conventionally plain and unornamented. The essential features of the design reside in the portions shown in solid lines.

I claim:

The ornamental design for a school plaque or the like, substantially as shown and described.
